SUGAR AND THE LIKE DISPENSER

Maria Garrido, New York, N. Y.

Application April 22, 1935, Serial No. 17,645

9 Claims. (Cl. 221—98)

This invention relates to new and useful improvements in a sugar and the like dispenser.

The invention has for an object the construction of a device as mentioned which is characterized by a container with an open top having a cylindrical neck, a hollow cylindrical member within the neck and having a cone-shaped bottom end, a cover, a cone-shaped member, and an inverted cup associated with the open end 5 of the receptacle in such a manner that a measured quantity of sugar may be dispensed each time the dispenser is inverted.

More particularly, the invention contemplates mounting the inverted cup fixedly spaced from the cylindrical member so that there is a passage for sugar around the edges thereof and locating the inverted cup between said cones so as to determine the amount of sugar dispensed each time.

Another one of the objects of this invention is 20 the provision of a novel means for adjustably holding the cup in several fixed positions to control the quantity of sugar dispensed at each operation of the device.

Still further the invention proposes the construction of a device as described which is simple and durable and which can be manufactured and sold at a reasonable cost.

For further comprehension of the invention, and of the objects and advantages thereof, reference will be had to the following description and accompanying drawing and to the appended claims in which the various novel features of the invention are more particularly set forth.

In the accompanying drawing forming a material part of this disclosure:—

Fig. 1 is a side elevational view of a device constructed according to this invention.

Fig. 2 is a plan view of Fig. 1.

Fig. 3 is a vertical sectional view of the device.

Fig. 4 is a horizontal sectional view taken on the line 4—4 of Fig. 3.

Fig. 5 is a horizontal sectional view taken on the line 5—5 of Fig. 3.

Fig. 6 is a perspective view of the cylindrical member per se.

Fig. 7 is a horizontal sectional view taken on the line 7—7 of Fig. 3.

The sugar and the like dispenser, according to this invention, comprises a container 10 with an open top portion 10^a and having a cylindrical neck portion 10^b. A hollow cylindrical member 11 is mounted within the neck portion and is formed with a cone-shaped bottom end 11^a. A cover 12 is engaged over the open top 10^a of the receptacle and is formed with a central opening

12^a connected with the central opening of a cup-shaped member 13 mounted between the cover 12 and the cylindrical member 11. An inverted cup 14 is spacedly held from said cylindrical member 13 so that there is a passage for sugar around the edges thereof and is located between the said cones, and is opposed to the said cone-shaped bottom end 11^a of the cylindrical member.

The container 10 is formed with a flat bottom 10^c so that it may rest upon a table or other flat object. Preferably the container should be constructed of glass, or other ornamental and attractive water-proof material. The cylindrical member 11 rests upon several lugs 15 integral 15 with the material of the container 10 and arranged immediately adjacent the bottom end of the cylindrical neck 10^b. With this arrangement the cylindrical member 11 may be manually drawn upwards and out from the open end 10^a 20 of the container. The cone-shaped bottom end 11^a is formed with a central opening 16 through which the sugar may pass against the cup 14.

The cup 14 is held by several straps 18 fixedly upon the cone-shaped member 13. A flange 19 25 surrounds the opening 12^a of the cover and telescopically engages with a flange 13^a of annular form, forming an opening in the base of the cone-shaped member 13.

The bottom periphery of the cone-shaped 30 member 13 is formed with several prongs 20 engaging into longitudinal grooves 21 formed in the inner face of the bottom cylindrical member 11. These prongs 20 terminate in resilient 35 portions 20' adapted to be wedged into branch 35 passages 21' of the groove 21 so as to fixedly hold the cone-shaped member 13 in various selected positions. In one position the cone-shaped member 3 is adapted to move longitudinally, and then rotated in several longitudinal positions so 40 as to maintain the longitudinally adjusted position. With this arrangement the space between the cup 14 and the opening 16 may be changed to control the amount of sugar dispensed each time the device is operated.

The cover 12 is removably mounted upon the open end 10^a of the container by several short inturned flanges 12^b upon the free edge thereof adapted to engage with undercuts in the outer wall of the end 10^a. The operation is similar 50 to that of screw threads. The connection means of the cover and the receptacle are not important since any other arrangement may be utilized without affecting the operation of the device.

The operation of the device is as follows:—The 55

5 cover 12, the cone-shaped member 13, and the cylindrical member 11 may be removed when it is desired to fill the receptacle 10 with sugar or other similar granulated food. The cylindrical member 11 is engaged into place, the cone-shaped member 13 is mounted upon the cylindrical member 11 in any one of its positions as desired, and finally the cover 12 is engaged in place. When the device is inverted the sugar 10 will spill through the opening 16 into the cup 14.

When the receptacle is returned to its upright position some of the sugar will fall downwards upon the upper face of the cone-shaped bottom end 11a of the cylindrical member 11. When the 15 receptacle is again inverted the sugar which has been deposited upon the upper face of the cone-shaped end 11a will be dispensed around the cup 14 and through the opening 12a. Simultaneously, another charge of sugar will be dispensed 20 into the cup 14. The operation continues in this fashion.

25 While I have illustrated and described the preferred embodiment of my invention, it is to be understood that I do not limit myself to the precise construction herein disclosed and the right is reserved to all changes and modifications coming within the scope of the invention as defined in the appended claims.

30 Having thus described my invention, what I claim as new, and desire to secure by United States Letters Patent is:—

35 1. A sugar and the like dispenser, comprising a container open at the top and having a cylindrical neck, a hollow cylindrical member within said neck and having a cone-shaped bottom end, a cover for the top of said container and having a central opening, a cone-shaped member having an opening connected with said central opening, and an inverted cup spacedly held from said cylindrical member so that there is a passage for the sugar around the edges thereof and located between said cones.

40 2. A sugar and the like dispenser, comprising a container open at the top and having a cylindrical neck, a hollow cylindrical member within said neck and having a cone-shaped bottom end, a cover for the top of said container and having a central opening, a cone-shaped member having an opening connected with said central opening, and an inverted cup spacedly held from said cylindrical member so that there is a passage for the sugar around the edges thereof and located 45 between said cones, said cylindrical member being removable through the open top end of said cylindrical neck.

45 3. A sugar and the like dispenser, comprising a container open at the top and having a cylindrical neck, a hollow cylindrical member within said neck and having a cone-shaped bottom end, a cover for the top of said container and having a central opening, a cone-shaped member having an opening connected with said central opening, and an inverted cup spacedly held from said cylindrical member so that there is a passage for the sugar around the edges thereof and located 50 between said cones, said cylindrical member being removable through the open top end of said cylindrical neck, and several projections from the bottom of the cylindrical neck for supporting the cylindrical member when in position within the cylindrical neck.

55 4. A sugar and the like dispenser, comprising a container open at the top and having a cylindrical neck, a hollow cylindrical member within said neck and having a cone-shaped bottom end, 60 a cover for the top of said container and having a central opening, a cone-shaped member having an opening connected with said central opening, and an inverted cup spacedly held from said cylindrical member so that there is a passage for the sugar around the edges thereof and located 65 between said cones, said cover being of dome shape and arranged with the opening in the top central portion thereof.

60 5. A sugar and the like dispenser, comprising 10 a container open at the top and having a cylindrical neck, a hollow cylindrical member within said neck and having a cone-shaped bottom end, a cover for the top of said container and having a central opening, a cone-shaped member having an opening connected with said central opening, and an inverted cup spacedly held from said cylindrical member so that there is a passage for the sugar around the edges thereof and located 15 between said cones, said cup being held by several strips in unison with said cone-shaped member.

15 6. A sugar and the like dispenser, comprising 15 a container open at the top and having a cylindrical neck, a hollow cylindrical member within said neck and having a cone-shaped bottom end, a cover for the top of said container and having a central opening, a cone-shaped member having an opening connected with said central opening, and an inverted cup spacedly held from said cylindrical member so that there is a passage for the sugar around the edges thereof and located 20 between said cones, said cup being held by several strips in unison with said cone-shaped member, and said inverted cone-shaped member having several prongs engaging in longitudinal grooves upon the inner wall of the hollow cylindrical member.

25

25 7. A sugar and the like dispenser, comprising 30 a container open at the top and having a cylindrical neck, a hollow cylindrical member within said neck and having a cone-shaped bottom end, a cover for the top of said container and having a central opening, a cone-shaped member having an opening connected with said central opening, and an inverted cup spacedly held from said cylindrical member so that there is a passage for the sugar around the edges thereof and located 35 between said cones, said cup being held by several strips in unison with said cone-shaped member, and said cone-shaped member having several prongs engaging in longitudinal grooves upon the inner wall of the hollow cylindrical member, 40 said prongs having resilient ends engageable in certain of a plurality of branches communicating with said grooves to hold the cup in various fixed adjusted positions to control the quantity of dispensed sugar.

45

7. A sugar and the like dispenser, comprising 50 a container open at the top and having a cylindrical neck, a hollow cylindrical member within said neck and having a cone-shaped bottom end, a cover for the top of said container and having a central opening, a cone-shaped member having an opening connected with said central opening, and an inverted cup spacedly held from said cylindrical member so that there is a passage for the sugar around the edges thereof and located 55 between said cones, said container having a flat bottom upon which it may rest on a flat surface.

8. A sugar and the like dispenser, comprising 60 a container open at the top and having a cylindrical neck, a hollow cylindrical member within said neck and having a cone-shaped bottom end, a cover for the top of said container and having a central opening, a cone-shaped member having an opening connected with said central opening, and an inverted cup spacedly held from said cylindrical member so that there is a passage for the sugar around the edges thereof and located 65 between said cones, said cover being of dome shape and arranged with the opening in the top central portion thereof.

70

9. A sugar and the like dispenser, comprising 70 a container open at the top and having a cylindrical neck, a hollow cylindrical member within said neck and having a cone-shaped bottom end, a cover for the top of said container and having 75

5 a central opening, a cone-shaped member having an opening connected with said central opening, and an inverted cup spacedly held from said cylindrical member so that there is a passage for
5 the sugar around the edges thereof and located between said cones, said cup being held by several strips in unison with said cone-shaped member,
10 and said cone-shaped member having several prongs engaging in longitudinal grooves upon the inner wall of the hollow cylindrical member,

said prongs having resilient ends engageable in certain of a plurality of branches communicating with said grooves to hold the cup in various fixed adjusted positions to control the quantity of dispensed sugar, and telescopically engaging cylindrical portions from the cover and the cone-shaped member for connecting the opening of the cone-shaped member with the central opening in the cover. 5
